ARTIFICIAL FISH BAIT

Anthony Accetta, Cleveland, Ohio

Application September 8, 1949, Serial No. 4,904

Term of patent 14 years

(Cl. D31—4)

To all whom it may concern:

Be it known that I, Anthony Accetta, a citizen of the United States, residing at Cleveland, in the county of Cuyahoga and State of Ohio, have invented a new, original, and ornamental Design for an Artificial Fish Bait, of which the following is a specification, reference being had to the accompanying drawing, forming a part thereof.

In the drawing:

Figure 1 is a perspective view of an artificial fish bait, showing my new design;

Figure 2 is a side view;

Figure 3 is a top plan view;

Figure 4 is a bottom plan view; and

Figure 5 is a front view.

The essential features of my design reside in the portions that are illustrated in full lines.

I claim:

The ornamental design for an artificial fish bait, substantially as shown and described.

ANTHONY ACCETTA.
